UNITED STATES PATENT OFFICE.

EDWARD BRICE KILLEN, OF LONDON, ENGLAND.

WHEEL AND WHEEL FITMENT.

Application filed September 15, 1919. Serial No. 323,954.

To all whom it may concern:

Be it known that I, EDWARD BRICE KILLEN, of 27 Queen Victoria Street, London, E. C. 4, England, engineer, have invented 5 certain new and useful Improvements in or Relating to Wheels and Wheel Fitments, of which the following is a specification.

This invention relates to wheels of a somewhat similar type to those described in my 10 previous specification No. 297149, and may be constructed interchangeable, reversible and divisible.

In my previous specification the wheel proper was constructed from two plain 15 dishlike stampings or plates, which I called the front and back dishlike stampings of the wheel, but said dishlike stampings were not constructed alike, whereas in this invention the front and back stampings are constructed 20 exactly alike and are bolted together back to back to form the divisible wheel.

In order that my invention may be properly understood and readily carried into effect, I have hereunto appended drawings, of 25 which—

Figure 1 shows the application of the invention to the construction of a simple disc wheel.

Figure 2 shows a method of attaching the 30 wheel to a hub shell or fitment.

Figure 3 shows the attachment of the additional face stampings to a simple disc wheel.

Figure 4 shows a method of constructing 35 distance or packing pieces to increase the thickness of the wheel centrally if required.

Figure 5 shows an alternative method of fitting distance or packing pieces between the two main dishlike stampings.

40 Each front and back main metal stamping 1 has a truly circular rim part 2. The metal, after forming the bed circumference, runs outward and may form a hooking flange 3 at the stamping's extreme overhanging edge, see Figures 1, 2, 3 and 5 enabling say an inflated or rubber tyre or wood felloe, as wanted, to be clamped, hooked and keyed in position at the wheel's circumference: but the metal in each stamping after 45 being say bolted together back to back on the wheel's centre line 4 at about an inch from the wheel's rim runs toward the wheel's centre and is suitably stamped with a dishlike cavity 15 which I will 50 call the central boss cavity of each stamping. This central boss cavity 5 is con-

structed capable of having a distance piece of wood 6, or its equivalent, keyed within it, which wood strengthens the wheel's part, and when the two main metal stampings 1 60 are fitted together back to back the wood in each boss cavity may meet on the centre line of wheel 4, forming a strong and solid driving central part 8 in the divisible wheel, see Figures 1, 2 and 3. The central cavity 5 65 formed in each main metal stamping is stamped to suit the special work for which the wheel is wanted, see Figures 1, 2, 3 and 5.

In addition to the main front and back dishlike stampings 1, I may if required use 70 two additional face stampings 9 or their equivalent, which I call the front and back face parts of the wheel see Figure 3. Each front and back face part 9 when used, is suitably attached or keyed to each front and 75 back main dish like stamping 1, without interfering with the divisibility of the wheel on its centre line 4, see Figures 3 and 5, and the front and back face parts 9, or their equivalents, when used, may give extra 80 strength to the divisible wheel by supporting the right and left overhanging circumference parts 10 of the wheel, see Figure 3. The right and left halves of the divisible wheel, which meet on the wheel's centre line 85 4, are held together by suitable bolts and nuts 7, or their equivalent.

In each of the two main front and back dishlike stampings 1 the central boss cavity 5 may be constructed having a standardized 90 depth of suitable dimensions thereby enabling the width of the wheel to be standardized centrally, and when the central part of the wheel is required to be wider, suitable distance pieces 11 and 12 see Figure 2, or 13 95 see Figure 4, are used to give the required width and strength to the wheel centrally. These suitable distance pieces may be constructed from metal 11 or 12 see Figure 2, or from suitable stampings 15 having wood 100 14 keyed within them, see Figure 4, and may be suitably riveted or attached to the central boss part of the wheel to give the required width or strength at the central part of the wheel, to suit many varying types of hubs or 105 hub fitments without interfering with the divisibility of the wheel on its centre line 4, or with its reversibility and interchangeability, or its clamping circumference.

In my divisible wheel suitable holes 15 in 110 stampings 1, see Figures 1 and 2, or 16 in stampings P see Figure 3, may be perfo-

rated in said stampings to give the wheel a light appearance and facilitate its divisibility, and any type of suitable distance piece of wood or other suitable material or materials 17, may be used and fitted at the central part of the wheel between the two main dishlike stampings 1 see Figure 5.

In this invention the wheel and its fittings may be constructed in all suitable dimensions and of suitable materials.

Claim:

A detachable disc wheel with a front and back face dishlike stamping manufactured alike, in which the metal runs unbroken 15 from the wheel's center to its circumference, each stamping having a central boss cavity, the two stampings being divisibly attached

back to back to form a hooking and clamping tire retaining circumference, and with an inner circumference which is reversible 20 on its hub without changing the wheel's center line and is strengthened by means of riveted central metal plates, and having additional suitable central distance pieces which allow the wheel to be suitably fitted 25 to existing types of hubs or hub shells, substantially as described.

In testimony whereof I affix my signature in presence of two witnesses.

EDWARD BRICE KILLEEN.
